UNITED STATES PATENT OFFICE.

WALTER D. STINSON, OF AUGUSTA, MAINE, ASSIGNOR TO HARTLEY E. SMITH, OF SAME PLACE.

DESIGN FOR A BADGE.

SPECIFICATION forming part of Design No. 15,478, dated October 21, 1884.

Application filed August 1, 1884. Term of patent 3½ years.

To all whom it may concern:

Be it known that I, WALTER D. STINSON, a citizen of the United States, residing at Augusta, in the county of Kennebec, in the 5 State of Maine, have invented and produced a new and original Design for Badges; and I do hereby declare the same to be described in the following specification and represented in the accompanying drawing, which is a plan 10 of it.

It is a square or rectangle, A, in shape, having at two of its opposite diagonal corners two triangles, B and C, in color contrasting with a space, D, between them, and in such space

the representation or figure, E, of the cone of 15 a tree—such as a pine, for instance—such being the leading features of my design.

I claim—

The above-described design for a badge, consisting of the square or rectangular body 20 having the two triangles, in color contrasting with the diagonal space between them, and the conventionalized representation of a pine cone in such space, as shown and described.

WALTER D. STINSON.
